(57) CLAIM

I claim the ornamental design for a container for brewing beer, as shown.

DESCRIPTION

FIG. 1 is an upper front perspective view of a container for brewing beer including left and right handles in flipped out positions.

FIG. 2 is a top plan view of the container for brewing beer of FIG. 1, with the left and right handles in farther flipped out positions.

FIG. 3 is a bottom plan view of the container for brewing beer of FIG. 1, with the left and right handles in the farther flipped out positions.

FIG. 4 is a front elevation view of the container for brewing beer of FIG. 1, with the left and right handles in flipped in positions.

FIG. 5 is a rear elevation view of the container for brewing beer of FIG. 1, with the handles in the flipped in position. FIG. 6 is a right side elevation view of the container for brewing beer of FIG. 1, with the right handle in the flipped in position; and,

FIG. 7 is a left side elevation view of the container for brewing beer of FIG. 1, with the left handle in the flipped in position.

1 Claim, 6 Drawing Sheets
